UNITED STATES PATENT OFFICE.

MARTIN TWORSKI, OF VANCOUVER, BRITISH COLUMBIA, CANADA.

INSUBMERGIBLE VESSEL.

Application filed January 6, 1921, Serial No. 435,300. Renewed December 6, 1922.

To all whom it may concern:

Be it known that I, MARTIN TWORSKI, citizen of Poland, residing at Vancouver, in the county of Vancouver and Province of 5 British Columbia, Canada, have invented certain new and useful Improvements in Insubmersible Vessels, of which the following is a specification.

This invention relates to floats and their 10 application to ships to either prevent the latter from sinking, or raise them after sinking, or for use as rafts or in the construction of pontoons.

The invention has for one object to provide a ship with a novel arrangement of collapsible floats whereby sinking of the latter 15 may be prevented in case of damage to the hull of the ship.

Another object is to provide an arrangement for coupling the floats in collapsed condition to a sunken ship whereby the latter 20 may be raised by inflation of the float.

Other objects relate to the detail construction of the float members themselves 25 and the securing of the same in groups.

For further comprehension of the invention, and of the objects and advantages thereof, reference will be had to the following description and accompanying drawings, 30 and to the appended claims in which the various novel features of the invention are more particularly set forth.

Fig. 1 of the drawings is a plan view of a ship having the invention applied thereto.

Fig. 2 is an enlarged fragmentary transverse section on the line 2—2 of Fig. 1.

Fig. 3 is a detail vertical section on the line 3—3 of Fig. 2.

Fig. 4 is a detail perspective view, with 40 parts broken away, of the float.

Fig. 5 is a side elevation showing the float and its cage as applied to the raising of the sunken ship.

Fig. 6 is an end view of the device shown 45 in Fig. 5.

Fig. 7 is a detail plan view showing the manner of joining a series of floats together to form a raft or pontoon.

Fig. 8 is a partial underside plan view of 50 the device as in Fig. 7.

Fig. 9 is an end view thereof.

Fig. 10 is a detail cross section of one of the floats, showing also a pump connected thereto.

55 Referring now to Figs. 1 to 3, the reference numeral 10 indicates the hull of an

ordinary ship, one of the lower decks being shown at 11. According to my invention a series of shallow pockets or recesses 12 are formed in the hull above the deck 11, these 60 recesses being of greater length than height. While I have shown the hull 10 as formed with a pair of these recesses on each side thereof it is to be understood that the number may be increased if desired. 65

Under normal conditions these pockets are covered by doors such as 15 fixed on arms 16, these arms being hinged on pintles formed by longitudinal shafts 17 located at the tops of the pockets and fixed at their 70 ends in the end walls of the pockets. To enable the doors to be swung outward when desired the arms 16 are extended beyond the hinged upper sides of the doors into the interior of the hull, slots 18 being formed 75 in the walls of the pockets to accommodate these extensions which form lever arms whereby the doors may be raised, and through the medium of which the doors are locked in closed position as will be presently 80 pointed out, the inner ends of the arms 16 being connected by a channel beam 20.

These pockets have positioned therein the collapsed float members 21 which are adapted to be inflated with air when put into use. 85 For inflating these floats I provide an air compressor 22 which may be driven by an electric motor 23, branched pipes 24 leading from the air compressor to the different pockets and connecting to the floats therein. 90 These floats may be attached on opposite sides to the inner walls of the pockets and the doors so as to be retained firmly in position when inflated.

The doors 15 are each locked in closed 95 position by a latch 25 in the form of a bar mounted between its ends on a pin 26 pivoted in a bracket 27 fixed on the hull 10 of the ship, one end of the bar 25 engaging the channel beam 20. Projecting over the 100 opposite end of the bar 25 is the hooked upper end of a bolt 28 slidable in a bearing 29 fixed to the channel beam 20, this bolt 28 having a pair of fixed collars 30 located on opposite sides of the bearing so as to 105 allow limited movement of the bolt. A tension spring 31, connected to an arm 32 on the hinge pin 26 normally presses the latch 25 into engagement with the beam 20.

Connected to the opposite end of the bolt 110 28 to that engaging the latch 25 is a rope 34 which extends downwardly and over a

drum 35 fixed on a shaft 36 mounted in suitable bearings on the deck 11, it being understood that there is one of these drums for each door, while only two of the shafts 5 are provided, each of which has the drums for the doors on one side of the ship fixed thereon, these shafts being driven by electric motors 37 through the medium of suitable reduction gearing, not shown. Under 10 normal conditions the operative end of latch 25 engages the channel beam 20 and holds the door closed. The latch is retained in this position by the action of spring 31 which holds the other end of the latch pulled upward 15 against the hook on bolt 28, upward movement of the bolt being limited by the lower collar 30 thereon bearing against the bottom of bearing 29, this being the position of the parts shown in Figs. 2 and 3. 20 When rope 34 is pulled, the bolt 28 is moved downward and swings latch 25 free of the beam 20, downward movement of the bolt being limited by the upper collar 30 thereon bearing against the upper end of the 25 bearing 29. Continued pulling on the rope 34 causes the door to open, as will be apparent.

The motor 23 for operating the air compressor 22, and the motors 37 just referred 30 to may be connected to common lead wires 40 and 41 in one of which is a hand switch 42 whereby the circuit may be closed. In one of the individual leads 43 to each of the 35 motors 37 is a switch comprising a pair of contacts 42', 43' fixed on a block 44 on one of the pockets 12 under one of the arms 16, these contacts being normally closed, but being opened when the arm 16 swings downward and engages a button 44 on the contact 43', thereby stopping the motors 37 without interfering with the motor 23.

In Fig. 4 of the drawings I have shown the preferred construction of the collapsible floats. These are preferably constructed to 45 be of cylindrical shape when inflated and comprise an inner bag 45 of rubber over which is a covering 46 of canvas or the like. The canvas covering is formed with a slit 47 for the insertion or removal of the rubber bag, the edges of this slit being secured by lacing 48. This lacing is preferably covered by a flap 49 secured to the cover 46 and extending over the lacing 48, this flap being laced in turn to a narrower flap 50 also secured to the cover. To ensure against the 50 edges of these flaps catching against objects, and to render the joints water-tight, these edges including the laced edges may be covered with plastic rubber or rubber cement 55 as indicated at 51.

In Figs. 5 and 6 I have shown an application of the invention to raising sunken ships. In this arrangement any desired number of the floats 21 may be employed. Each of the 60 floats has secured to opposite sides thereof,

in any suitable manner the I-beams 55, 56 and looped between these I-beams on opposite sides of the float are chains 57 suitably spaced along the floats. Secured to the lower I-beam 56 is a hook 58, while a 70 rope or cable 59 is attached to the upper I-beam 55. In operation the floats are let down into the water to the sunken ship in collapsed condition the hook 58 being then attached to the ship. It will be understood 75 of course that the weight of the I-beams and chains will be sufficient to sink the floats when collapsed. Air is then pumped into the float through a flexible pipe 60 leading thereinto, which pipe may be wire-wound or otherwise suitably reinforced. The floats when filled with air will exert a lifting force 80 on the vessel to raise the latter to the surface.

In Figs. 7 to 10 I have shown my improved 85 float as applied to the construction of a portable raft, or of a pontoon bridge. In this embodiment the floats are arranged side by side in pairs of which there may be any number disposed end to end, each pair being 90 separated by a partition composed of plates 65 joined by rope loops 66.

To hold the floats together I employ a series of ropes 66 extending longitudinally therealong, of which there is preferably one 95 at each side, two at the top, and two at the bottom. These longitudinal ropes are lashed together by cross ropes arranged as follows: Extending between the bottom ropes 66 are short ropes 68 which are secured thereto at 100 opposite ends as at 67. To these bottom ropes a second series of ropes 69 are attached, these ropes being carried first upwardly around one side of the raft and looped as at 70 and 71 around the adjacent side and 105 top rope 66, then carried across diagonally in a crossed formation as at 72 to the other top rope 66, looped around the same and the other side rope as at 73 and 74 and finally secured as at 75 to the other bottom rope. 110 The partition plates 65, above referred to are also connected by rope fastenings 76 to these longitudinal ropes 66. For inflating the raft structure a pipe 77, branched as at 78, may connect to the end pair of floats 21, 115 while each float may be connected to the next one, longitudinally considered, by a flexible pipe 79 in which is a valve 80. In Fig. 10 I have indicated one of the floats 21 as being inflated by a hand pump 81, which 120 may be carried round with the device when used as a portable raft by hunters or others.

Having thus described my invention what I claim as new and desire to protect by Letters Patent of the United States is as 125 follows:

1. In a ship, a series of pockets formed in the hull thereof, doors normally closing said pockets, collapsed floats in said pockets, said doors having fixed arms extending upward 130

along the inner face of the hull, latch-bars pivotally mounted between their ends and having one end, engaging said arms to hold the doors closed, operating means for said doors, and hooked elements connected to the door operating means and adapted to release the said latch-bars on operation of the said means.

2. In a ship, a series of pockets formed in the hull thereof, doors normally closing said pockets, collapsed floats in said pockets, said doors having fixed arms extending upward along the inner face of the hull, latch-bars pivotally mounted between their ends and having one end engaging said arms to hold the doors closed, operating means for said doors, and hooked elements connected to the door operating means and adapted to release the said latch-bars on operation of the said means, said hooked elements comprising sliding bolts, guide bearings therefor, and collars on said bolts on opposite sides of the guide bearings, for the purpose specified.
- 25 3. In a ship, a series of pockets formed in the hull thereof, doors normally closing said pockets, collapsed floats in said pockets, said doors having fixed arms extending inwardly into the hull, said arms being in close prox-

imity to the inner face of the hull when the doors are closed, and means in said hull connected to said arms to operate the doors.

4. In a ship, a series of pockets formed in the hull thereof, doors normally closing said pockets, collapsed floats in said pockets, said doors having fixed arms extending inwardly into the hull, said arms being in close proximity to the inner face of the hull when the doors are closed, electrically operated means for opening said doors, and a switch adapted to be engaged by said doors when opened to cut out the current to the door operating means.

5. In a ship, a series of pockets formed in the hull thereof, collapsed floats in said pockets, doors normally closing said pockets, said doors having arms extending into the hull, latches engaging said arms to hold the doors closed, operating means for the doors, said operating means having lost motion connections with the doors, and members connected to said operating means adapted to release said latches on initial movement of the operating means.

In testimony whereof I have affixed my signature.

MARTIN TWORSKI.
